UNITED STATES PATENT OFFICE.

THOMAS A. CROMPTON, JR., OF ILFORD, ENGLAND.

VENTILATING, FIRE-EXTINGUISHING, AND STEAMING APPARATUS FOR GASOLENE OR OTHER TANKS.

1,302,318.

Specification of Letters Patent.

Patented Apr. 29, 1919.

Application filed January 31, 1916. Serial No. 75,259.

To all whom it may concern:

Be it known that I, THOMAS ALBERT CROMPTON, Jr., a British subject, and residing at 29 Clarendon Gardens, Ilford, in the county of Essex, England, have invented a new and Improved Ventilating, Fire-Extinguishing, and Steaming Apparatus for Gasoline or other Tanks, of which the following is a specification.

10 My invention relates to an improved apparatus for safely ventilating gasoline or other tanks containing inflammable liquids and giving off inflammable gases, also for fire-extinguishing and steaming of such tanks. This apparatus is designed to allow the safe escape of inflammable or other dangerous gases from storage tanks, but only when such escape is necessary owing to the increased pressure arising from whatever cause, such as expansion or filling up of tank or other causes. The apparatus will also operate automatically should a partial vacuum exist within the tank due to contraction or emptying, at all other times the tank 25 to which apparatus is fitted being hermetically sealed, thus preventing loss of gasoline or other liquids by evaporation.

A further object of the present invention is to enable the same conduit which is used 30 for ventilation purposes to be used for steaming the tank, either for cleaning purposes or to extinguish fire.

These objects are attained by the mechanism illustrated in the accompanying drawing, in which the figure is a vertical part sectional drawing of apparatus and showing in section all working parts.

35 A is the automatic arrangement for ventilating and allowing for the safe escape of gases.

B is the connection fitted on tank top and allows the tank to be in communication with atmosphere through the device A or with the steam line as may be required.

40 C is the cone arrangement or circulator and is fitted within tank immediately under and connected to B.

D is the inner pipe reaching to near bottom of tank and fitted with a steam spreader 45 E at base of pipe.

50 For the ventilating and relief of pressure or vacuum in tank, the top or ring valve Q comes into operation, the drawing shows a part cross section with pressure and vacuum valves, removable cage seating, adjusting

screws, lock nuts, springs and gauze wire screen in position. The valve chamber F has a projection or seating G and forms when valve cage LKP is in position an air tight joint. The bottom end of valve chamber can be screw-threaded internally or externally or flanged as found suitable for connecting on pipe leading down to connection B. The top of valve chamber F is screwed externally to take cover H. This cover is screwed internally and has a projection or flange I which binds on flange of gauze wire screen J thereby thrusting this against the upper end of the valve cage so that this in turn is thrust down against the inner flange G with which it makes an air-tight joint. The wire screen is made of suitable brass or copper gauze pressed out and fitted with brass flange as indicated. The cover is cast with grooves between screw-threaded portion and outer rim for the escape and intake of gases or air. The cover is also intended to prevent any grit, dirt or water gaining access to valve chamber and for the escape of explosive and dangerous gases. The removable valve cage LKP has a center ring with miter seating for the reception of pressure and vacuum valves and a flat seating which when cage is in position forms the tight joint at G. The top ring L of cage is screwed internally for the reception of grating ring M. This ring has a central boss N for carrying adjusting screw O. The bridge piece P under center ring in removable cage is for carrying adjusting screw O¹ and lower spring S¹. The pressure valve Q is a double miter grating valve, the inner miter forming the seat for spindle valve R. Valves Q and R are as near equal in area as possible and are held in position by springs S and S¹ and adjusted by screws O and O¹, these screws being locked by fly nuts T and T¹. The bottom spring S¹ takes the weight of both valves, so allowing either valve to practically float on their seats and 55 to act with the slightest variation of pressure. The top ventilating device A may be fitted direct on valve chamber B or be connected to same by length of piping as may be required. For gas freeing of tanks especially with regard to oil tank vessels a steam jet arrangement may be interposed between the device A and the valve chamber B pointing in an upward direction and when in action would tend to exhaust all explosive 60

or other dangerous gases from tank. Valve chamber B together with cone arrangement C are fitted direct to wall of tank, the former outside and the latter inside tank with 5 inner piping and steam spreader D and E attached. A branch pipe L enters valve chamber B. Its end is turned upward, the top forming valve seat U. Double miter valve V rests on this seat. Top seating W 10 for valve V is screwed externally and fitted in recess of top flange of chamber B. Cone attachment C is constructed with an internal tube X and has several openings Y through large part of outer casing. This attachment is connected inside tank immediately 15 under valve chamber B. The pipe D is secured by flanges or screwed to bottom part of C, extending nearly to bottom of tank and is fitted at lower end with a cone shaped 20 spreader E.

Under normal conditions gasoline or other liquid storage tanks fitted with above apparatus would be hermetically sealed and would thus prevent any loss from evaporation. 25 In the event of any accumulating pressure within tank the gas or air would pass through openings Y, enter internal tube X and ascending upward and passing over top of valve V would enter valve chamber A, when the pressure acting on the under side of spindle valve R would lift same together with grating valve Q, so allowing 30 escaping gas to emerge into atmosphere, passing through gauze wire screen J and 35 grooves of cover H. The direct opposite of above takes place when a partial vacuum occurs in tank due to contraction of contents or when pumping out, but in this case grating valve Q remains on its seat, the atmospheric 40 pressure acting through this valve on spindle valve R opening same in a downward direction and so admitting air into tank. By this means atmospheric pressure is always maintained within tank.

45 For fire-extinguishing and steaming of tanks, steam would be admitted to the main conduit or by the branch pipe Z. This enters with a rush and in large volume so that it lifts the double miter valve V to top seating W where it is held as there is no resisting pressure on the opposite side, the valve thus shutting off all communication to outer atmosphere and allows steam to enter tank for the purpose of extinguishing fire, 50 or steaming out through openings Y or spreader E as may be necessary and which the height of liquid in tank should determine, an injector effect being produced in the perforated conical part C.

55 I am aware that it has heretofore been proposed to provide a feed pipe, having a 60

portion constituting a valve chamber, opening into a tank with a branch pipe opening into the valve chamber, two float controlled valves having a weighted balancing device 65 being provided for controlling the ends of the valve chamber connected to the two portions of the feed pipe. In this known device, both valves were normally open and no valve was provided for controlling the 70 end of the branch pipe opening into the valve chamber, and I do not claim the same broadly; but—

I claim:—

1. In apparatus for ventilating and steaming containers for volatile liquids, the combination with a container, of a main conduit having one end portion opening into the same, an intermediate or second portion constituting a valve chamber, and the other end 80 or third portion opening into the valve chamber by way of an upper valve seat therein, a branch conduit having one end terminating at a lower valve seat in the valve chamber, and a double-faced lift valve 85 adapted to be seated alternately on said seats and normally seated on said lower seat and in this position closing the said end of the branch conduit, whereby the container is normally in open communication with the 90 said third portion of the main conduit, but is shut off therefrom when the said valve is lifted against the said upper seat by fluid under pressure entering the valve chamber through the branch conduit. 95

2. In apparatus for ventilating and steaming containers for volatile liquids, the combination with a container, of a main conduit having one end portion opening into the same, an intermediate or second portion constituting a valve chamber, and the other end or third portion opening into the valve chamber by way of an upper valve seat therein, a branch conduit having one end terminating at a lower valve seat in the 100 valve chamber, and a double-faced lift valve 105 adapted to be seated alternately on said seats and normally seated on said lower seat and in this position closing the said end of the branch conduit, the upper part of the 110 said first end portion of the main conduit located in the container being bulged and provided with openings, and a nozzle forming a part of the conduit and projecting down through the bulged portion, for the 115 purpose specified.

Dated this 13th day of Jan., 1916.
